(**) Term: **14 Years**

The ornamental design for a cover for an insect trap that utilizes propane gas, as shown and described.

DESCRIPTION

FIG. 1 is a perspective view of a cover for an insect trap that utilizes propane gas, the design being shown in context and characterized by a cover that shields both the propane tank and the insect trap when they are in a side-by-side arrangement.

FIG. 2 is an elevated perspective view of the cover shown in FIG. 1;

FIG. 3 is a top view of same;

FIG. 4 is a front view thereof, the back being a mirror image thereof; and,

FIG. 5 is a side view thereof; and,

FIG. 6 is a bottom view thereof.
